(57) **CLAIM**

The ornamental design for a soap holder, as shown and
described.

DESCRIPTION

FIG. 1 is a top, right, front perspective view of a soap holder
showing my new design;

FIG. 2 is a front elevation view thereof;

FIG. 3 is a rear elevation view thereof;

FIG. 4 is right side elevation view thereof;

FIG. 5 is a left side elevation view thereof;

FIG. 6 is a top plan view thereof; and,

FIG. 7 is a bottom plan view thereof.

The broken line showing is for the purpose of illustrating
unclaimed portions of the article and forms no part of the
claimed design.
